United States Patent Office

Des. 183,499
Patented Sept. 9, 1958

183,499

STOCKING DRYER

Paul F. Simpson, Washington, Conn., assignor to The Autoyre Company, Oakville, Conn., a corporation of Connecticut

Application November 21, 1955, Serial No. 38,955

Term of patent 14 years

(Cl. D33—16)

Fig. 1 is a front elevational view of a stocking dryer showing my new design, and

Fig. 2 is a side elevational view.

The dominant features of my design reside in those portions shown in full lines on the drawing.

I claim:

The ornamental design for a stocking dryer, substantially as shown, and described.
